UNITED STATES PATENT OFFICE.

HANS HENRIK BLACHE, OF HELLERUP, NEAR COPENHAGEN, DENMARK.

FUEL-OIL TANK IN TWIN-SCREW MOTOR-SHIPS.

1,319,947.

Specification of Letters Patent.

Patented Oct. 28, 1919.

Application filed August 2, 1919. Serial No. 315,023.

To all whom it may concern:

Be it known that I, HANS HENRIK BLACHE, a citizen of the kingdom of Denmark, residing at No. 32 Sofievej, Hellerup, near 5 Copenhagen, Denmark, have invented certain new and useful Improvements in Fuel-Oil Tanks in Twin-Screw Motor-Ships, of which the following is a specification.

In motor ships it is advisable to store a 10 portion of the fuel oil in elevated tanks having no walls in common with the ship's side, nor any walls immediately adjacent to the ship's side, as the ship may have to pass through such cold climates that the cold 15 would make it necessary to heat the oil, in order to render it sufficiently liquid. Even when the oil is heated, it will not be sufficiently liquid, if the storage tank is partly formed by the ship's side, or is placed in direct contact with the same, as the heat supplied will then quickly be carried away by the cold water.

The present invention remedies this drawback by locating the tank, in twin-screw 25 motor ships, between the shaft-tunnels of the two propeller-shafts, the tank in this position being very easy to construct, as the side walls of the shaft-tunnels may be utilized as side walls in the tank which is 30 closed, at top, by the same horizontal bulkhead that forms the ceiling in the shaft-tunnels.

The drawing illustrates one manner of constructing the invention.

35 Figure 1 shows, diagrammatically, the device in top-view.

Fig. 2 shows a vertical cross-section of the same.

Referring to Fig. 1, "a" indicates the engine-room which is closed by the rear bulkhead "b." "c" and "d" indicate the ship's principal Diesel-engines, which drive the propeller shafts "g" and "h." The propeller-shafts "g" and "h" are located, in 40 usual manner, in shaft-tunnels "e" and "f." According to this invention, the oil-tank or tanks are located between the shaft-tunnels, so that the oil in the tank or tanks will be 45 protected against transmission of heat to the sea. According to the invention, the oil-tank is built in such a manner that the side walls of the shaft-tunnels form the side 50 walls of the oil-tank, while the same hori-

zontal plates which form the ceiling and floor in the shaft-tunnels will also form the 55 top and bottom of the oil-tank.

In the construction shown, the oil tank is limited fore and aft by two walls "i" and "k" placed transversely in relation to the ship, the wall "i" being placed at some distance from the aft bulkhead "b" in the engine-room, while the wall "k" is located at some suitable distance from the next transverse bulkhead "m," so that there are formed 60 passages "o" and "n" between the shaft-tunnels; and so that the further advantage is attained that the oil-tank is insulated, by means of these passages, from the surrounding fore-and-aft and athwart-ship's bulkheads.

The tank, which is surrounded on all four sides by free passages, is eminently suitable 65 for storage of oil, and it is especially easy to heat the oil in the tank, as the heat-transmission to the surroundings is exceedingly 70 slight. The heating of oil may be effected in ordinary known manner, by means of steam-coils or the like built into the tank.

I claim as my invention:

1. In a twin-screw ship, the combination, 80 with a pair of propeller shafts and a tunnel for each shaft, said tunnels being spaced from each other and from the adjacent sides of the hull; of a fuel tank disposed in the space between the shaft-tunnels so as to be 85 insulated by said tunnels against temperature changes in the sea water and also against appreciable loss of heat by heat transmission when the fuel is heated in the tank, substantially as described.

2. In a twin-screw ship, the combination, 90 with a pair of propeller shafts and a tunnel for each shaft, said tunnels being spaced from each other and from the adjacent sides of the hull; of a fuel tank disposed in the 95 space between the shaft-tunnels, and connecting passages between the tunnels disposed at opposite ends of the tank, whereby the tank is surrounded on all four sides by free air passages which insulate against temperature changes in the sea water and which enable the fuel in the tank to be heated without appreciable loss of heat by heat transmission.

In testimony whereof I affix my signature. 105
HANS HENRIK BLACHE.
